ARTICLE OF FOOTWEAR WITH GATHERED
VAMP MEMBERLewis P. Carpenter, Scituate, Mass., assignor to
The B. F. Goodrich Company, New York, N. Y.,
a corporation of New York

Application January 29, 1947, Serial No. 725,109

3 Claims. (Cl. 36—11.5)

1

This invention relates to an article of footwear, and particularly to a play shoe or slipper of simple construction having a moccasin-like vamp.

The principal objects of this invention are to provide an article of footwear, such as a play shoe or a slipper, having a simple construction; to provide an article which may be worn comfortably wherein the vamp and quarter of the shoe may be adjusted to fit closely about the foot or to fit loosely about the foot as desired; to make an article which protects the wearer's foot without confining it in an enclosed assembly; and to make such an article in a simple and economical manner to give a shoe of neat and pleasing appearance.

Foot comfort is a prime requisite in the construction of play shoes or slippers. Such comfort is predicated on a number of factors, including protection for the plantar surface of the foot; ease in keeping the shoe in a form-fitting condition about the foot; ease of donning and doffing without slippage of the shoe on the foot while being worn; adjustability of the shoe upper; and means for allowing the foot to "breathe."

The shoe must be of simple construction so that a minimum number of operations are required in making it. The component parts of the shoe must be of such shape that they can be easily prepared and are economical as to materials. The finished assembly, furthermore, must present a neat and pleasing appearance.

By means of this invention an article of footwear such as a play shoe or slipper is simply and economically constructed in an assembly possessing the necessary requisites for foot comfort. The article comprises a moccasin-like vamp having a lacing which is detachably engaged by the forward portion of the quarter, whereby the article is held in a foot-fitting assembly. The invention is best understood by reference to a preferred embodiment as illustrated by the accompanying drawings of which:

Fig. 1 is a perspective view of the vamp member used in the construction of a preferred embodiment of the invention;

Fig. 2 is a plan view of the quarter member which has been prepared as the next step in the construction of the shoe;

Fig. 3 is a perspective view of the vamp and quarter members attached to an insole to form a shoe-like assembly; and

Fig. 4 is a perspective view of the finished assembly illustrating the manner in which the shoe is kept in a form-fitting condition.

In constructing a preferred embodiment of the invention as illustrated by the drawings, an elongated trapezoidal vamp member 10 is cut preferably from a sheet of duck fabric, although leather or other suitably flexible material may be used. The marginal regions 11, 11 adjacent to the non-

2

parallel ends 12, 12 of the member are folded back and stitched at 13 to form reinforced edges. A plurality of spaced openings 14, 14 are cut in the vamp member 10 in the longitudinal, marginal region adjacent the shorter of the two parallel edges 15 thereof. Through these spaced openings 14, 14 is threaded a drawstring lacing 16 of substantially greater length than the vamp member 10 with the free ends of the lacing extending beyond the ends of the vamp member.

In the next operation, a pair of quarter portions 17, 17 are cut from a sheet of duck fabric; although, as in the case of the vamp member, other suitable materials such as leather may be used. The quarter portions 17, 17 are stitched together at 18 to form a generally H-shaped quarter member with the legs 19, 19 being slanted upwardly away from each other. The circumferential margin 20 of the quarter member 17 is folded back and stitched down in a folded, reinforced edge 22. Eyelets 23, 23 are inserted in the quarter member 17 near the top of each generally vertically-extending leg 19 of the member.

A suitably shaped insole member 24 is provided of leather, fabric or other suitable material. The lower ends 25, 25 of the quarter member legs 19, 19 are folded under the opposite sides 26 and 27 of the heel portion 28 of the insole member 24 so as to extend over the marginal region 29 of the lower face 30 of the insole 24. Similarly, the longer of the two parallel edges 31 of the vamp member 10 is folded under the toe portion 32 of the insole 24 over the marginal region 29 of the lower face 30 of the insole 24. The vamp and quarter members are then joined to the insole by a line of stitching 33 in the marginal region 29 to give a shoe-like assembly as shown in Fig. 3. In this assembly the cross member 34 of the generally H-shaped quarter member 18 forms a strap-like heel-encircling portion 34 which terminates forwardly in the forwardly-inclined legs 19, 19 of the quarter 18 which extend upwardly so as to overlie the instep of a wearer's foot. In this condition, the eyelets in the quarter member are adapted to releasably engage the free ends of the lacing with the vamp member pulled inwardly over the insole.

A layer of cement 35 is spread over the lower face 30 of the insole 24 and a platform-type outsole 36 of suitable shape and material is positioned on the lower face of the insole and held in position by the cement, or the outsole may be secured by other suitable means. With the attachment of the outsole the shoe is finished and ready for wear.

When the shoe is donned, as shown in Fig. 4, the free ends 31, 37 of the lacing 16 are crossed over the foot and inserted through the eyelets 23, 23 in the quarter member 18 so that the free end of the lacing from the inner end of the vamp

passes through the eyelet in the leg on the outer side of the foot and vice-versa. The lacing may then be pulled as tightly as desired and tied. This pulls the upper edge of the vamp 10 inwardly so as to enclose a forward portion of the foot and holds the quarter member against the foot in a form-fitting assembly, which may be adjusted as desired and which does not slip on the foot in walking. The sole portion protects the plantar surface of the foot, while the discontinuous upper portion formed by the vamp and the quarter member is open enough to allow the foot to "breathe."

The upper portion comprising vamp and quarter members may be of any flexible material of which the various textiles and soft leather are especially suitable. The insole and outsole similarly may be of any suitable material, such as leather or rubber, and the means of attaching the vamp and quarter may be varied to include cementing and similar means, as well as stitching as described in the preferred embodiment. Other similar variations and modifications may be effected within the scope of the invention, such as other fastening means on the legs of the quarter member, and using a one-piece quarter member.

An article of footwear constructed in accordance with this invention is easily donned and doffed, may be adjusted to fit closely or loosely about the foot as desired, can be worn without slippage on the foot while walking, provides protection for the plantar surface of the foot, and allows the foot to "breathe." The method of making the article involves a minimum number of simple operations, and the shape of the component parts is such as to be economical of materials. The finished article is of neat and pleasing appearance.

The invention has been described in detail with reference to certain preferred embodiments and a few preferred variations and modifications thereof, but it will be understood that other variations and modifications may be effected in the method and the article of footwear without departing from the spirit and scope of the invention as defined in the appended claims.

I claim:

1. An article of footwear comprising a sole, a narrow elongated flexible continuous closed vamp member of substantially uniform width having its lower longitudinal margin secured to said sole around the marginal extent of the toe portion thereof from substantially the front end of the shank portion of the sole at one side thereof to substantially the front end of the shank at the opposite side of the sole and having its rear ends folded inwardly and having a plurality of spaced openings throughout the extent of the upper longitudinal margin of said member including said folded rear ends, a draw-string lacing associated solely with said vamp member threaded through said openings along the upper margin of said vamp member parallel to said margin with the free ends of the lacing extending in diagonally crossed relationship rearwardly beyond the ends of the vamp member, and a quarter member secured to said sole terminating in forwardly and transversely extending instep-overlying ends having engaging means for releasably engaging the free ends of said lacing to gather the upper margin of said vamp member and said ends of the quarter member inwardly.

2. An article of footwear comprising a sole, a narrow elongated flexible continuous closed vamp member of substantially uniform width having its lower longitudinal margin secured to said sole around the marginal extent of the toe portion thereof from substantially the front end of the shank portion of the sole at one side thereof to substantially the front end of the shank at the opposite side of the sole and having its rear ends folded inwardly to form a reinforced rear margin extending upwardly and forwardly and having a plurality of spaced openings throughout the extent of the upper longitudinal margin of said member including said folded rear ends, a draw-string lacing associated solely with said vamp member threaded through said openings along the upper margin of said vamp member parallel to said margin with the free ends of the lacing extending in diagonally crossed relationship rearwardly beyond the ends of the vamp member, and a quarter member secured to said sole terminating in forwardly and transversely extending instep-overlying ends having eyelets for releasably engaging the free ends of said lacing to gather the upper margin of said vamp member and said ends of the quarter member inwardly.

3. An article of footwear comprising a sole member including an insole and an outsole, a narrow elongated flexible continuous closed vamp member of substantially uniform width having its lower longitudinal margin secured between said insole and outsole around the marginal extent of the toe portion thereof from substantially the front end of the shank portion of said sole member at one side thereof to substantially the front end of the shank at the opposite side of the sole member and having its rear ends folded inwardly upon themselves to form a reinforced rear margin extending upwardly and forwardly, a draw-string associated solely with said vamp member slidably engaged along the upper margin of said vamp member parallel to said margin and passing through openings in said reinforced rear margins with the free ends of said draw-string extending in diagonally crossed relationship rearwardly beyond the ends of the vamp member, and a quarter member having its lower margin secured between said insole and outsole terminating in forwardly and transversely extending instep-overlying ends having engaging means for releasably engaging the free ends of said draw-string to gather the upper margin of said vamp member and said ends of the quarter member inwardly.
